CONTROL APPARATUS FOR A PLURALITY
OF MOTORS

Harry C. May, East McKeesport, Pa., assignor to
The Westinghouse Air Brake Company, Wil-
merding, Pa., a corporation of Pennsylvania

Application July 31, 1945, Serial No. 607,926

13 Claims. (Cl. 60—97)

1

This invention relates to control apparatus of the type employed to manually control fluid pressure operated motors for obtaining movement in more than one plane of a device such as a gun turret, searchlight or any device which is to be pointed at a particular object.

The principal object of the invention is to provide an improved control apparatus of the above mentioned type.

Another object of the invention is to provide a control apparatus of the above type which is capable of producing either vertical or horizontal movement, or any combination of the two movements, at any desired rate of speed.

A further object of the invention is to provide, in a control apparatus of the above type employing a motor which is operated in response to fluid under pressure supplied from a continuously driven fluid pressure pump under the control of a manually operated control valve device, means responsive to the flow of fluid permitted by the valve device to condition the pump to automatically increase or decrease the supply of fluid under pressure according to the requirements of the apparatus.

The foregoing and other objects, which will become apparent upon reading this specification in conjunction with the accompanying drawings, may be attained by means of the particular apparatus shown in the various figures wherein:

Fig. 1 is a diagrammatic view, chiefly in section, of a preferred embodiment of the invention;

Fig. 2 is an elevation sectional view taken on the line 2—2 through a portion of the apparatus shown in Fig. 1;

Fig. 3 is a sectional view of the same taken on the line 3—3 in Fig. 1; and

Fig. 4 is a diagrammatic view, partly in section, of a modified form of the invention.

Description

As shown in Fig. 1 of the drawings, the control apparatus may comprise a rotary hydraulic pump 1, a duplex control valve device 2, a rotary hydraulic motor 3, a sump reservoir 4, and an actuating cylinder 5.

The rotary hydraulic pump 1 is of the variable displacement type and comprises a supercharging portion 6 and a high pressure pump portion 7, both portions being mounted in a common casing 8. The supercharging portion 6 comprises a pair of hydraulic pump gears 9 operatively mounted in a chamber 10 formed in the casing 8, the inlet side of the chamber being connected by way of passage and pipe 11 and pipe 12 to the sump res-

2

ervoir 4, and the outlet side of the chamber being connected by way of passages 13 and 14 to an inlet port 15 in a rotary valve seat (not shown) in the high pressure pump portion 7.

The high pressure pump portion 7 comprises a drive shaft 16 having formed integrally therewith a cylinder 17 provided with a plurality of bores 18 and arranged to be rotatably mounted in a chamber 19 in the casing 8, which chamber is connected to the outlet of reservoir 4 by way of pipe 12. The drive shaft 16 is ported so as to effect the proper charging and discharging connections from the bores 18 to the inlet port 15 and an outlet port 20 in the aforementioned rotary valve seat (not shown) which is slidably engaged by the end of the shaft. Slidably and rotatably mounted in the bores 18 of the cylinder 17 are a plurality of pistons 21 which may move outwardly in response to centrifugal force developed by the rotation of the cylinder and also fluid pressure until a beveled edge 22 on the outer end of each piston engages an inner race 23 of a roller bearing 24 which surrounds the cylinder 17. The bearing 24 is provided with an outer race 25 having two straight and parallel opposite facing outer surfaces so that horizontal movement of the bearing 24 may be guided by caged bearings 26 acting thereon.

For automatically positioning the roller bearing 24 according to the flow of fluid under pressure permitted by the control valve device 2, the pump 1 is further provided with an operating mechanism 27, which mechanism comprises a casing 28 mounted by suitable means (not shown) to the left-hand side of the casing 8 of the pump 1. Formed in a section of the casing 28 is a chamber 29 open at one end to the chamber 19 and containing an operating stem 30, the left-hand end of which stem engages the outer race 25 of the bearing 24. The other end of the stem is pivotally connected with one end of an unloading lever 31. Interposed between and operatively engaging the right-hand wall of the chamber 29 and a spring seat 32 carried on the stem 30 is a spring 33 for actuating the bearing 24 to the right for the purpose of increasing the displacement of the pistons 21 as will hereinafter more fully appear. The lever 31 is pivotally mounted at its other and upper end to the casing 28 and is arranged to be engaged intermediate its ends by a piston 34 in such a manner that, when actuated outwardly, the piston 34 will cause the stem 30 to move in a direction away from the bearing 24 and against the pressure of the spring 33. The piston 34 is carried in a bore 35 formed in the cas-

ing 28, the bore being constantly in open communication by way of a passage 36 with a pump delivery passage 37.

At the right-hand side as viewed in Fig. 1, the race 25 is provided with a boss 38 for slidable engagement with a shiftable control cam 39, the vertical movement of which cam causes the race to be shifted horizontally in the bearings 26, thereby cutting the pump 1 into and out of high pressure operation as the demand requires. This cam 39 is carried by a pair of opposed pistons 40 and 41 operatively disposed in piston chambers 42 and 43, respectively, the piston 40 and chamber 42 being the larger in diameter for reasons which will appear more fully later. The piston chamber 42 is in constant communication by way of a passage 44 with check valve chambers 46, 47 and 48 above the ball check valves 49, 50 and 51 contained respectively therein, and also by way of passage 44, and a choke 44a to a pipe 45. The piston chamber 43 is connected by way of a passage and pipe 52 to the delivery passage 37 and to a chamber 53 in the casing 8, which chamber contains a check valve 54 biased toward its seat against the fluid pressure in passage 13 by a light spring 55.

The duplex control valve device 2 is provided for the purpose of controlling the flow of fluid under pressure supplied from the pump 1 to the rotary hydraulic motor 3 and the actuating cylinder 5 and the discharge of fluid therefrom. This control valve device 2 may be of the same general type as that shown and described in my application Serial No. 496,868, filed in the United States Patent Office, July 31, 1943, and assigned to the assignee of the present invention.

The duplex control valve device 2 may comprise a lower body casing 56 and an upper body casing 57, the body casing 56 being provided with a central bore 58 which is closed at its upper end by a wall 59 and at its lower end by a cap member 60 which may be secured to the bottom of the casing 56 by any suitable means (not shown). As shown in Figs. 1 and 2, there is provided in the casing 56 near its upper end a port 61 which is open to the bore 58 and is connected by way of passage and pipe 62 to a chamber 63 at one side of a piston 64 in the actuating cylinder 5. Near its lower end the casing 56 is provided with a similar port 65 which is also open to the bore 58 and is connected by way of a passage and pipe 66 to a chamber 67 at the other side of the piston 64 in the actuating cylinder 5. In vertical alignment with the ports 61 and 65 and midway between them a supply port 68 is provided in the casing 56, which port is open to the bore 58 and is connected to the delivery passage 37 of the high pressure pump portion 7 of the pump 1 by way of the passage 69 and pipe 52. To the left of the supply port 68 as viewed in Figs. 1 and 3 the casing 56 is provided with a port 70 through which fluid under pressure may be supplied by way of passage and pipe 71 to the rotary motor 3 to effect the operation thereof in one direction. For effecting the operation of the motor 3 in the opposite direction, a port 72 is similarly provided in the casing to the right of the supply port 68 and is connected to the motor 3 by way of a passage and pipe 73. For reasons which will herein-after more fully appear, the pipes 71 and 73 are connected to the under sides of the ball check valves 51 and 49, respectively, in the pump 1 by way of the respective pipes 74 and 75.

For controlling the flow of fluid under pressure through the aforementioned ports a valve 76 is

operatively mounted in the bore 58 for both rotary and vertical movement therein. This valve 76 is provided with a central bore or discharge passage 77 which is connected to the delivery passage 13 of the supercharging portion 6 of the pump 1 by way of the bore 58 and a discharge passage and pipe 78. For effecting communication between this discharge passage 77 and either chamber 63 or 67 of the actuating cylinder 5, the valve 76 is provided with a radially extending through passage 79 which may be brought into registration with the port 61 by downward linear movement of the valve 76 and also a radially extending through passage and port 80 which may be brought into registration with the port 65 by upward linear movement of the valve 76. A similar passage and port 81 may be brought into registration with the port 70 by horizontal rotation of the valve 76 to the right and another 20 similar passage and port 82 may register with the port 72 upon horizontal rotation of the valve 76 to the left, thereby controlling the discharge of fluid from the rotary motor 3. For the control of the flow of fluid under pressure to the actuating cylinder 5 or the rotary motor 3, or both, the valve 76 is provided with a cavity 83 which is in constant open communication with the supply port 68 in the bore 58, which port, as previously mentioned, is connected by way of pipe 69 to the delivery passage 27 of the pump 1. This cavity 83 is so constructed and arranged that when fluid is discharged from one side of the cylinder 5 or the motor 3, the cavity 83 will become effective to supply fluid under pressure to the other side to effect the operation of that device.

The upper body casing 57 is retained in rotatable relation to the lower body casing 56 by means of a disc member 84 and the wall 59 of the casing 56 to which the disc member may be rigidly secured by any suitable means such as cap screws 84a. Formed integrally with the disc member 84 and interposed between a pair of oppositely disposed spring actuated plungers 85 and 86 carried in the casing 57 is an upright ear 87, against which the plungers may react to yieldably urge the casing 57 to rotate to a central neutral position. For imparting movement to the valve 76 said valve is provided with an integral stem 88 which extends through suitable apertures 40 in the casing 56 and the disc member 84 to make within the casing 57 a positive connection with one end of a link 89. This link 89 makes at its other end a pivotal connection with a pin 90 carried by a shaft 91 which is horizontally and 45 rotatably mounted in the casing 57. Formed integrally with the shaft 91 and interposed between a pair of opposed spring actuated plungers 92 and 93 disposed at right angles to the shaft 91 is an upright lug 94 against which the plungers 92 and 93 may react to yieldably urge the shaft to rotate toward a central neutral position. The shaft extends through suitable bearings 95 in the casing 57 and at each end terminates in a suitable handle 96, whereby the shaft may be rotated axially to impart longitudinal movement to the valve 76 and whereby the shaft may be rotated end for end to impart rotary movement to the valve 76.

Operation

Let it now be assumed that this control apparatus is being used in connection with a gun turret, that the rotary motor 3 is utilized to obtain the desired traverse of the gun turret, that the actuating cylinder 5 is utilized to obtain the

proper elevation of the gun, and that both the turret traverse and the gun elevation are obtained through the manipulation of the control valve device 2 by the gunner. It will also be assumed that the various parts associated with the several devices described are in the position in which they are shown in Fig. 1, and that the pump 1 is being driven at a constant speed by an electric motor (not shown) or other power means.

Fluid will be supplied from the sump reservoir 4 by way of pipe 12 and inlet passage 11 to chamber 10 in the supercharging portion 6 of the pump 1. The gears will be rotated in the directions to supply fluid under pressure to the inlet port 15 of the high pressure pump portion 7 by way of passages 13 and 14. This fluid under pressure in the passage 13 will also be supplied at a low degree of pressure past the check valve 54 and by way of passage 37 to provide a cushion and thereby obtain smoother performance when the pump is first put into operation. Fluid under pressure in passage 13 will also be supplied by way of pipe 78 to a chamber 100 in a check valve device 101 mounted in the sump reservoir 4. Should the fluid pressure in the chamber 100 exceed a selected degree such as 75 pounds per square inch, the excess pressure will cause a piston valve 102 to move to its unseated position against the opposing pressure of a spring 103 thereby permitting the excess fluid under pressure to pass to the sump until the pressure is reduced to 75 pounds.

It will be understood that the bearing 24 will, in the normal position in which it is shown in Fig. 1, be disposed in the chamber 19 so that its center lies slightly to the right of the center of the shaft 16 and the cylinder 17. In this normal position the pump is conditioned for the delivery of fluid at a pressure of 300 pounds per square inch. As the cylinder 17 is rotated the pistons 21 are held by centrifugal force of the rotation and fluid pressure in engagement with the inner periphery of the inner race 23 of the bearing 24. Because of the aforementioned eccentricity between the bearing 24 and the cylinder 17 the pistons 21 will be permitted to move outwardly in the lower half of their path of travel and forced inwardly in the upper half of their path of travel. While the pistons are moving outwardly the bores 18 in which they are mounted are connected by way of ports 104 in the shaft 16 to the inlet port 15 in the rotary valve seat (not shown) and while the pistons are moving inwardly the bores 18 are connected by way of the ports 104 to the outlet port 20. Thus fluid will normally flow from the supercharging portion 6 at a pressure of 75 pounds by way of passages 13 and 14, inlet port 15, ports 104 to the bores 18 in the cylinder 17 and thence by way of ports 104, outlet port 20, and passage 37 to pipe 52, at a pressure of 300 pounds.

It should be understood that although fluid under pressure in passage 37 is communicated by way of pipe 52 to the piston chamber 43 the relation of the areas of the pistons 40 and 41 is such that the 300 pounds pressure in the piston chamber 43 acting on the piston 41 will balance with the previously mentioned 75 pounds fluid pressure in the chamber 42 acting on the piston 40. Under this balanced condition the cam 39 will be maintained in the position in which it is shown in Fig. 1.

Now if the gunner wishes to decrease the angle of elevation of the gun, he will rotate the handles 96 of the control valve device 2 in a coun-

terclockwise direction from the neutral position in which it is shown in Fig. 1 of the drawings. This movement will cause the shaft 91 to also rotate counter-clockwise about its axis against the opposing pressure exerted by a spring 105 acting through the medium of the plunger 92 on the lug 94 which is integral with the shaft. The shaft 91 will act through the medium of the pin 93, link 89, and stem 88 of the valve 76 to move said valve in a vertically downward direction. Downward movement of the valve 76 may be continued until the valve is brought to a stop by the bottom of the valve engaging the inner surface of the cap member 60.

As the valve 76 is moved downwardly the supply port 68 is connected to the chamber 67 in the actuating cylinder 5 by way of port 65 and passage and pipe 66. At the same time the chamber 63 at the opposite side of the piston 64 in the actuating cylinder 5 is connected to the discharge pipe 78 by way of pipe 62, ports 64 and 79, and discharge passage 77. With these communications established, fluid under pressure is supplied to chamber 67 at the lower side of the piston 64 in the actuating cylinder 5 and fluid under pressure at the upper side of piston 64 is discharged so that the piston 64 is caused to move upwardly from the position. This upward movement of the piston will cause a shaft 106 associated with the cylinder to rotate in a direction for decreasing the angle of elevation of the gun.

When the gunner releases his grip on the handle 96 of the control valve device 2, the spring 105, acting through the medium of the plunger 92 and the lug 94 of the shaft 91, causes the shaft to rotate in a clockwise direction and thereby return the handle 96 to its neutral position. At the same time the valve 76 is caused to move upwardly to its neutral position, in which position the ports 61 and 65 in the casing 56 are lapped. Further flow of fluid under pressure to chamber 67 and discharge of fluid under pressure from the chamber 63 is cut off, so that the piston 64 will be maintained in its adjusted position.

Now when the gunner wishes to increase the angle of elevation of the gun, the necessary downward movement of the piston is obtained by rotating the handle 96 of the control valve device 2 from its neutral position in a clockwise direction about the axis of the shaft 91 as viewed in Fig. 1. Clockwise rotation of the shaft 91 causes the lug 94 to actuate the plunger 93 against the opposing pressure of a spring 107 and at the same time acts through the medium of the link 89 and stem 88 to impart upward movement to the valve 76. Upward movement of the valve 76 connects the supply port 68 in the casing 56 of the control valve device 2 with the chamber 63 at the upper side of the piston 64 in the actuating cylinder 5 by way of cavity 83, port 61 and pipe 62 while connecting the chamber 67 at the opposite side of the piston 64, to the discharge pipe 78 by way of pipe 66, ports 65 and 80, and discharge passage 77. With these communications established, the pressure of fluid in chamber 63 is increased and the pressure of fluid in chamber 67 is decreased, thus causing the piston 64 to move downwardly.

When the desired elevation of the gun is reached, the gunner may release his grip on the handle 96 and the handle, together with the shaft 91, is rotated counter-clockwise to neutral position by the pressure of the spring 107 acting through the medium of the plunger 93 and the lug 94. The pressure of the spring also acts 75 through the medium of the shaft 91, link 89 and

stem 88 to move the valve 76 downwardly to its neutral position therebylapping the ports 61 and 65 in the casing 56 and again cutting off communication with the chambers 63 and 67 in the actuating cylinder 5, so that the piston 64, and therefore the gun, will be held in the desired position.

It will be understood that during all of the operations previously described herein, the pump 1 is operated continuously in its normal position in which it is shown, or to the right thereof, to thereby maintain a fluid pressure of 300 pounds in the delivery passage 37 and pipe 52 in a manner now to be described. It will also be understood that a pressure of 300 pounds is sufficient to operate the actuating cylinder 5 any time when a change in the elevation of the gun is desired.

It will be apparent that when the flow of fluid under pressure to the control valve device 2 is cut off, the pressure of fluid in the pipe 52, and likewise in the connected piston chamber 43, will rise rapidly if the output of the pump 1 continues at the same rate. It will be remembered that the pressure of fluid in chamber 42 acting downwardly on the piston 40 remains constant at 75 pounds against which 300 pounds fluid pressure acting upwardly on the piston 41 is balanced. Consequently, when the fluid pressure in chamber 43 increases above 300 pounds the pistons 40 and 41 together with the cam member 39 will be caused thereby to move upwardly. Since cam member 39 extends gradually inwardly toward its lower end, upward movement of the cam member, acting through the medium of the boss 38, will cause the bearing 24 to be shifted toward the left against the opposing pressure of the spring 33, moving the bearing toward a position of concentric relation with the cylinder 17 and thereby reducing the output of the pump. This upward movement will continue until the delivery pressure is reduced to 300 pounds again and may be such that the pump is practically cut out. It will thus be seen that this combination of the pistons 40 and 41 and cam member 39 with the bearing 24 and spring 33 acts as a governor for the pump so as to limit the pressure of its normal output to 300 pounds.

The gunner may also effect the traverse of the gun turret in either direction by swinging the handles 96 of the control valve device 2 in arcs of a circle about the vertical axis of said device in the same direction as that desired for movement of the gun turret. When the gunner wishes to effect a traverse of the gun turret to the right, for example, he will swing the handles 96 in a clockwise direction from the neutral position in which they are shown in Figs. 1 and 2. This movement of the handles causes the shaft 91 and thereby the upper body casing 57 to rotate in the same direction.

As the upper body casing 57 is thus rotated, it moves relative to the lug 87 carried by the disc member 84 since the disc member is, as hereinbefore described, rigidly secured to the lower body casing 56. This rotative movement of the casing 57 causes the plunger 86 at the right-hand side of the lug 87 to move inwardly against the opposing pressure of a spring 108 and also acts through the medium of the shaft 91, pin 90, link 89 and stem 88 to rotate the valve 76 in a clockwise direction about its axis as viewed in Fig. 3. By referring to Fig. 3 it will be apparent that such movement of the valve 76 will establish communication between the supply port 68 and the passage and pipe 73 by way of the cavity 83 in the

valve and port 72 in the casing. At the same time said valve establishes communication between the pipe 71 and the discharge pipe 78 by way of port 70 in the casing 56, discharge port 81 and the discharge passage 77 in the valve. With these communications established, fluid under pressure is supplied from the delivery passage 37 in the pump 1 by way of pipe 52, supply port 68, cavity 83, port 72, and passage and pipe 73 to the upper side of the motor 3 while fluid under pressure is discharged from the lower side of said motor by way of pipe and passage 71, ports 70 and 81, discharge passage 77 and discharge pipe 78. This flow of fluid under pressure will cause a shaft 109 of the motor 3 to rotate in a direction which, through suitable gear means (not shown) will effect the traverse of the gun turret to the right.

When the turret reaches the desired position, the gunner releases his grip on the handles 96 and the spring 108 exerts, through the medium of the plunger 86, a pressure on the lug 87 of the disc member 84, causing the upper body casing 57 in which it is mounted and thereby the shaft 91 and attached handles 96 to rotate in a counter-clockwise direction toward the horizontal neutral position. With this movement of the shaft 91, the valve 76 is rotated through the medium of the pin 90, link 89 and stem 88, in a counter-clockwise direction to its horizontal neutral position in which position the ports 70 and 72 in the casing are lapped. With communication with the motor 3 thus cut off the gun turret will be held in its newly acquired position.

It should here be understood that, the weight of the gun turret being many times greater than that of the gun, the work required to effect the traverse of the gun turret will likewise be many times greater than that required to change the elevation of the gun. Since it is highly desirable for reasons of economy of space to have a small motor or power means, it becomes necessary to use fluid at a high degree of pressure, such as 1,800 pounds, in order to effect the traverse of the gun turret promptly and quickly. Control means are accordingly provided for automatically cutting the pump 1 into high pressure operation by increasing its piston displacement when the gunner wishes to effect the traverse of the gun turret.

It should be noted, therefore, that the pipe 73 is also connected by way of pipe 75 to the under side of the ball check valve 49 in chamber 46 which chamber is connected by way of passage 44 to the piston chamber 42. Thus, when fluid under pressure at a degree of 300 pounds is supplied to pipe 73 as a result of the manipulation of the control valve device 2 as just previously described, fluid at a pressure of 300 pounds also flows by way of pipe 75 past ball check valve 49 and through passage 44 to the top of piston 40 in chamber 42. Although fluid at a pressure of 300 pounds is also supplied from the passage 37 to the face of the piston 41 in chamber 43 by way of pipe 52 in opposition to the downward pressure acting on the piston 40, the latter pressure will prevail because, as previously noted, the effective area of the piston 40 is greater than that of the piston 41. In response to the preponderance of downward pressure, the pistons 40 and 41 will move downwardly, thereby causing the cam member 39 to be actuated downwardly to a position defined by contact between the piston 41 and a cap member 110 closing the bottom of the chamber 43. In consequence of the pressure of

the spring 33 acting on the bearing 24 through the medium of the spring seat 32 and stem 30 to maintain the boss 38 of said bearing in slidable contact with the graduated surface 111 of the cam 39, the downward movement of the cam will permit the bearing race 24 to be shifted to the right as viewed in Fig. 1.

It will here be understood that if the center of the bearing 24 coincides with the center of the shaft 16 and cylinder 17 there will be no axial reciprocating movement of the pistons 21 in the bores 18. Consequently the pump portion 1 will not produce any flow of fluid under pressure. However, if the center of the bearing 24 is displaced to the right as viewed in Fig. 1 each of the pistons 21 will make one reciprocatory cycle for each revolution of the cylinder 1. The displacement of each piston 21 is substantially equivalent to the amount the center of the bearing 24 is displaced from the center of the shaft 17. It will be apparent, therefore, that when the bearing 24 is shifted to the right in the manner hereinbefore described, the flow of fluid under pressure to the delivery passage 37 will be increased in proportion to the degree of displacement of the center of the bearing to the right of the center of the shaft.

It should be further noted that by reason of the tapered ports in the control valve device 2, the speed of operation of the motor 3 and cylinder 5 and therefore the volumetric requirements will be varied. Since the pump 1 is operated at a constant speed, it follows that the pressure of fluid in the delivery pipe 37 will vary inversely to the flow of fluid away from the pipe. This varying pressure would prevent the gunner from anticipating with any degree of certainty how the motor 3 was going to respond to a certain manipulation of the control valve device 2. Therefore, the operating mechanism 27 of the pump 1 is provided to insure a constant 1,800 pound fluid pressure, and no more, being available for operation of the motor 3, and thus obviate the above undesirable condition.

Fluid under pressure in the passage 37 will flow by way of passage 36 to the face of the piston 34 in the bore 35, tending to move the piston to the left as viewed in Fig. 1 and rotate the lever 31 about its upper end. However, this movement is opposed by the pressure of the spring 33 acting on the lower end of the lever 31 through the medium of the spring seat 32 and stem 30. When the fluid pressure in the bore 35 exceeds 1800 pounds, the pressure acting on the piston will cause the piston to move toward the left. This movement will cause the lever 31 to rotate about its upper end in a clockwise direction, thereby moving the stem 30 against the opposing pressure of the spring 33 acting through the medium of the seat 32.

It should be explained that in a pump structure of the type described in connection with pump portion 1 the bearing 24 has an inherent tendency to return to its non-operative position, which in this example would be toward the left. Consequently, the bearing race 25 will follow the movement of the stem 30 to the left, thereby reducing the displacement of the pump portion 1. The reduced displacement will reduce the pressure in the delivery passage 37 and in the bore 35, which will continue until the piston 34 and the spring 33 reach a state of equilibrium. Should the pressure in the bore 35 be further reduced, the spring will act through the medium of the stem

30 to shift the bearing 24 to the right and thereby increase the pump displacement.

When the gunner released his grip, the spring 108, acting by means of the plunger 86 and the lug 87 of the disc member 84, caused the upper body casing 57 and thereby the shaft 91 and attached handles 96 to rotate in a counter-clockwise direction until it reached its neutral position. As the shaft 91 is rotated end-for-end in a counter-clockwise direction, the valve 76 is also rotated in a counter-clockwise direction through the medium of a pin 90, a link 89 and stem 88 to its neutral position, in which position the ports 70 and 72 in the casing 56 are lapped. With these ports lapped, the supply of fluid under pressure to and the release of fluid under pressure from the motor 3 is cut off and the gun turret will be held in its latest assumed position.

When the supply of fluid under pressure to the pipe 73 is cut off, the flow of fluid under pressure to the chamber 42 by way of pipe 75, check valve chamber 46 and passage 44 is likewise cut off. Since the chamber 42 is always open by way of the choke 44a and pipe 45 to the discharge pipe 78, fluid under high pressure in chamber 42 will flow to pipe 78 and thence past check valve 102 (set at 75 pounds) in chamber 100 to the sump in reservoir 4.

The fluid at high pressure in delivery passage 37 will still be communicated to the piston chamber 43 by way of the pipe and passage 52. As the pressure acting in a downward direction on the piston 40 is gradually reduced, the 1800 pound pressure acting upwardly on the piston 41 will become sufficient to actuate the cam 39 upward toward the position in which it is shown in Fig. 1. Upward movement of the cam 39 will act through the medium of the boss 38 to shift the bearing 24 to the left against the opposing pressure of the spring 30 and toward its normal position in which it is shown in Fig. 1.

When the gunner wishes the gun turret to move to the left, he may swing the handles 96 in a counter-clockwise direction from the neutral position in which they are shown, thereby acting through the medium of the shaft 91, to which they are attached, to rotate the upper body casing 57 in a counter-clockwise direction. This rotary movement relative to the fixed lug 87 will cause the plunger 85 at the left-hand side of the lug to be moved inwardly against the pressure of a spring 112.

Counter-clockwise rotation of the casing 57 also effects through the medium of the shaft 91, pin 90, link 89 and stem 88 the counter-clockwise rotation of the valve 76. As best shown in Fig. 3 this movement of the valve 76 will establish communication between the supply port 68 and the passage and pipe 71 by way of the cavity 83 in the valve 76 and port 70 in the casing 56. At the same time said valve establishes communication between the pipe 73 and discharge pipe 78 by way of port 72 in the casing 56, discharge port 82 and the discharge passage 77 in the valve 76. Thus fluid under pressure in the delivery passage 37 may be supplied by way of pipe 52, supply port 68, cavity 83, port 70, and passage and pipe 71 to the lower side of the motor 3 while fluid under pressure is discharged from the upper side of the motor 3 by way of pipe and passage 73, ports 72 and 82, discharge passage 77 and discharge pipe 78. This flow of fluid under pressure will cause the shaft 109 of the motor to rotate in a

direction which will effect the traverse of the gun turret to the left.

When the turret reaches the desired position, the gunner will permit the spring 112, exerting through the medium of the plunger 85 a pressure on the lug 87 of the disc member 84, to effect the clockwise rotation of the casing 57, and thereby the shaft 91 and handles 96 attached thereto, to the neutral position in which they are shown. This movement of the shaft 91 causes the valve 76 to be rotated through the medium of pin 90, link 89 and stem 88 clockwise to neutral position, in which position the ports 70 and 72 in the casing are again lapped.

It will be noted that the pipe 71 is also connected by way of pipe 74 to the under side of the ball check valve 51 in chamber 48 which chamber is also connected by way of passage 44 to the piston chamber 42. Thus, when fluid at a pressure of 300 pounds is supplied to the pipe 71 by manipulation of the control valve device 2, fluid at a pressure of 300 pounds also flows by way of pipe 74 past ball check valve 51 and through passage 44 to the top of piston 40 in chamber 42. The pump 1 will again be cut into high pressure operation to deliver fluid at a pressure of 1800 pounds in the same manner as previously described in connection with supplying fluid under pressure to pipe 73 to effect the traverse of the turret to the right.

It is thus made apparent that when fluid at a pressure of 300 pounds is supplied to either side of the motor 3, this fluid pressure will also be communicated to the face of the piston 40 in chamber 42 to effect thereby the operation of the pump to supply fluid at a pressure of 1800 pounds. When the flow of fluid under pressure to motor 3 is cut off the pump will return automatically to its normal position in which fluid under pressure is supplied at 300 pounds. When the actuating cylinder 5 is operated, the pump 1 will remain in normal position, but when the motor 3 is brought into operation, either alone or together with the cylinder 5, the pump 1 will automatically move to a high pressure position to supply fluid at a pressure of 1800 pounds.

The actuating cylinder 5 can be operated by the 300 pounds or 1800 pounds pressure, either being sufficient for its complete operation. Obviously, by permitting the pump to operate normally at 300 pounds pressure except when moving the turret, a more economical operation may be obtained.

In certain installations it has been found highly desirable to have a second control station at the commander's post, from which station the commander would be able when the occasion arose to intercept the gunner's control and assume the control himself. To attain this result there has been provided in this invention an additional duplex control valve device which may be connected in parallel with the duplex control valve device 2, and has in addition, an intercepting valve device interposed between the valve device 2 and the motor 3 and cylinder 5 for manual operation to cut off said communication.

Referring now to Fig. 4 of the drawings, there is shown a duplex control valve device 120, which device comprises a duplex control portion 121, which portion is shown only in outline since the structure and function are the same as those for the duplex control valve device 2. The control portion 121 is arranged to be supplied with fluid under pressure by way of pipe 52 as is valve device 2. The control portion is also arranged to

supply fluid under pressure to the actuating cylinder 5 by way of either a pipe 122 or a pipe 123 while discharging fluid under pressure from said cylinder by way of the other pipe. These pipes 122 and 123 are associated with control portion 121 in the same manner as are pipes 62 and 66, respectively, with valve device 2. The control portion is further arranged to supply fluid under pressure to the motor 3 by way of either a pipe 124 or a pipe 125 while discharging fluid under pressure from said motor by way of the other pipe. These pipes bear the same relation to control portion 121 as do pipes 71 and 73, respectively, to the control valve device 2.

Secured to the bottom of the casing for the duplex control portion 121 by any suitable means (not shown) is an intercepting valve device 126, which device comprises a casing 127 having formed therein a plurality of valve chambers 128, 129, 130 and 131 and cam chamber 132.

Operatively mounted in the chamber 128, which is in constant open communication by way of the pipe 124 with the motor 3, is a valve 133 which controls communication between said chamber and pipe and passage 71 connecting with the control valve device 2. Interposed between and operatively engaging the valve 133 and a cap nut 134 closing the bottom of chamber 128 is a spring 135 which constantly urges the valve upwardly toward its seated position. At its upper end the valve 133 terminates in a stem 136 which extends upwardly through a suitable opening in the casing 127 into the cam chamber 132 where it may be engaged by a cam surface 137 of a slideable cam member 138 so as to retain the valve in its unseated position in which it is shown in Fig. 4.

Operatively mounted in the valve chamber 129, which is in constant open communication by way of pipe 125 with the motor 3, is a valve 139 which controls communication between said chamber and pipe and passage 73 connecting with the control valve device 2. Interposed between and operatively engaging the valve 139 and a cap nut 140 closing the bottom of the chamber is a spring 141 which constantly urges the valve in an upward direction toward its seated position. At its upper end the valve 139 terminates in a stem 142 which extends upwardly through a suitable opening in the casing 127 into the cam chamber 132 where it may be engaged by a cam surface 143 of the cam member 138 so as to also actuate the valve 139 to its unseated position in which position it is shown in Fig. 4.

Operatively mounted in the valve chamber 130, which is in constant open communication by way of pipe 66 with the control valve device 2, is a valve 144 which controls communication between said chamber and pipe and passage 123 which connects with the actuating cylinder 5. Interposed between and operatively engaging the valve 144 and a cap nut 145 closing the lower end of chamber 130 is a spring 146 which constantly urges the valve upwardly toward its seated position. At its upper end, the valve 144 terminates in a stem 147 which extends upwardly through a suitable opening in the casing 127 into the cam chamber 132 where it may be engaged by a cam surface 148 of the cam member 138 so as to also actuate the valve 144 to its unseated position in which position it is shown in Fig. 4.

Operatively mounted in the chamber 131, which is in constant open communication by way of pipe 62 with the control valve device 2, is a valve 149 which controls communication between

said chamber and pipe and passage 122 which connects with the actuating cylinder 5. Interposed between and operatively engaging the valve 149 and a cap nut 150 closing the lower end of the chamber 131 is a spring 151 which constantly urges the valve upwardly toward its seated position. At its upper end the valve 149 terminates in a stem 152 which extends upwardly through a suitable opening in the casing 127 into the cam chamber 132 where it may be engaged by a cam surface 153 of the cam member 138 so as to actuate the valve 149 to its unseated position in which position it is shown in Fig. 4.

Thus it will be seen upon referring to Fig. 4 that, when the intercepting valve device 126 is in its normal position in which it is shown, fluid under pressure may flow between the control valve device 2 and the motor 3 in one direction by way of pipe 71, chamber 128 and pipe 124 while flowing in the opposite direction by way of pipe 125, chamber 129 and pipe 73. Likewise, one communication is established between the control valve device 2 and the actuating cylinder 5 by way of pipe 66, chamber 130 and pipe 123 while a similar communication is established by way of pipe 122, chamber 131 and pipe 62. It will be apparent therefore that so long as the intercepting valve device 126 remains in the position in which it is shown, the gunner may, by the manipulation of control valve device 2 as previously described, control the traverse of the gun turret and the elevation of the gun.

Now if the commander wishes to cut off the gunner's control and assume control himself he may move the cam member 138 toward the right, as viewed in Fig. 4, by means of handle 154 rigidly secured to the cam member, thereby moving the cam surfaces 137, 143, 148 and 153 relative to the valve stems 136, 142, 147 and 152, respectively, so that the valves may be caused to seat. The spring 135 will be permitted to actuate the valve 133 upwardly to its seat while spring 141 will be permitted to actuate the valve 139 to its seat. At the same time spring 146 will move valve 144 to its seat and valve 149 will be seated by the pressure of the spring 151. Since, as previously noted, the duplex control portion 121 is in constantly open communication with the motor 3 and the actuating cylinder 5 by way of pipes 122, 123, 124 and 125, it follows that the commander may now exercise, by means of the control portion 121, the same control over the gun and turret as the gunner had previously done by manipulation of the control valve device 2 hereinbefore described. Since the valves 133, 139, 144 and 149 are all seated, all control communications between the control valve device 2 are interrupted and movement of the handles 95 thereof will be entirely ineffective.

When the commander wishes to turn the control back to the gunner he may do so by moving the handle 154 and thereby the cam surfaces 137, 143, 148 and 153 of the cam member 138 to the left. This movement will act through the medium of stems 136, 142, 147 and 152 to cause their respective valves 133, 139, 144 and 149 to move downwardly out of their seated positions against the opposing pressures of the springs 135, 141, 146 and 151, respectively. With these valves unseated, the communications by which the gunner may control the operation of the motor 3 and actuating cylinder 5 will again be established.

Having now described my invention, what I claim as new and desire to secure by Letters Patent is:

1. In a rotary fluid pressure pump having a rotative portion and a non-rotative portion surrounding said rotative portion and movable into eccentric relation therewith, said non-rotative portion being shiftable to increase the degree of said eccentricity and thereby the output of said pump, the combination of constant pressure means for shifting said non-rotative portion in a direction for increasing the degree of eccentricity, a cam member having one position for limiting said shifting to a certain low predetermined degree and shiftable to another position to limit said shifting to a certain predetermined higher degree, and a movable abutment positively connected to said constant pressure means responsive to the pressure of fluid delivered by said pump to directly oppose said constant pressure means and counter-balance the same when a certain predetermined pressure of fluid is delivered.

2. A constant speed fluid pressure pump comprising in combination a rotatable portion, a bearing portion having a normal position relative to said rotatable portion and being shiftable therefrom to another position for increasing the displacement of said pump, a spring biasing said bearing portion toward said other position, a cam member for defining the movement of said bearing portion in response to the pressure of said spring, said cam member having a normal position in which said bearing portion is located in its normal position and being movable therefrom to a position in which said spring is permitted to shift said bearing portion to said other position, a movable abutment means responsive to fluid under pressure to move said cam member out of its normal position, and other movable abutment means responsive to the pressure of fluid supplied by said pump to limit the power of said spring when the pressure of the fluid supplied by said pump reaches a certain predetermined degree.

3. A constant speed fluid pressure pump equipment comprising in combination a rotatable portion, a bearing portion having a normal position relative to said rotatable portion and being shiftable therefrom to another position for increasing the displacement of said pump, a spring biasing said bearing portion toward said other position, a cam member for defining the movement of said bearing portion in response to the pressure of said spring, said cam member having a normal position in which said bearing portion is located in its normal position and being movable therefrom to a position in which said spring is permitted to shift said bearing portion to said other position, a relatively large piston which will respond to the pressure of fluid supplied from said pump to move said cam member out of its normal position, means for supplying fluid under pressure from said pump to said piston, means for cutting off the supply of fluid under pressure to said piston from said pump, means for reducing the pressure of fluid acting on said piston when the supply from said pump is cut off, and a relatively small piston subject at all times to the pressure of fluid supplied by said pump and responsive thereto to move said cam member to its normal position when the pressure of fluid acting on the first mentioned piston has been substantially reduced.

4. A control system for the manual control of fluid pressure operated motors for obtaining movement of a part in more than one plane, in combination, one motor responsive to fluid under pressure above a certain low degree to move said part in one plane; another motor responsive

to fluid at a pressure of a certain predetermined higher degree to move said part in another plane; a pump driven at a constant speed for supplying fluid under pressure to said motors; a control valve device interposed between said pump and said motors for controlling the supply of fluid under pressure to said motors; a second control valve device having connections in parallel with said first control valve device; and an intercepting valve device mounted on said second control valve device comprising a plurality of poppet valves controlling communication between the first mentioned control valve device and said motors, said valves being arranged to be actuated to their seated positions by spring pressure, cam member arranged to slidably engage the stems of said valves and shiftable relative thereto for actuating said valves out of their seated positions, and means for shifting said cam member; said pump comprising a rotative portion, a non-rotative portion having one position for effecting the operation of the pump to supply fluid under pressure at a degree sufficient to operate said one motor and being movable to another position for effecting the operation of the pump to supply fluid under pressure at a certain predetermined higher degree to operate said other motor, and means normally causing said non-rotative portion to assume said one position and responsive to the pressure of fluid supplied to said other motor to cause said non-rotative portion to shift to said other position.

5. A rotary pump arrangement comprising a supercharging portion, a high pressure pump portion, a member to be shifted to vary the output of the pump portion according to the distance the member is shifted, movable means operative for effecting the shifting of said member, said means comprising a small piston subject at all times to the high pressure of fluid delivered by said high pressure pump portion and also comprising a larger piston normally subject to the relatively low pressure of fluid delivered by said supercharging portion acting in opposition to pressure of fluid on said small piston and responsive to an increase in the pressure of fluid acting thereon to shift said member for increased output of the pump portion, and means operative to effect the flow of fluid under pressure from said high pressure pump portion to said larger piston to thereby increase the pressure of fluid acting on said larger piston.

6. A rotary pump arrangement comprising a supercharging portion, a high pressure pump portion, a member to be shifted to vary the output of the pump portion according to the distance the member is shifted, movable means operative for effecting the shifting of said member, said means comprising a small piston subject at all times to the high pressure of fluid delivered by said high pressure pump portion and also comprising a larger piston normally subject to the relatively low pressure of fluid delivered by said supercharging portion acting in opposition to pressure of fluid on said small piston and responsive to an increase in the pressure of fluid acting thereon to shift said member for increased output of the pump portion, means operative to effect the flow of fluid under high pressure from said high pressure pump portion to said larger piston to thereby increase the pressure of fluid acting on said larger piston, and means for reducing the pressure acting on said larger piston to the relatively low pressure of fluid delivered by said supercharging portion.

7. A fluid pressure pump equipment comprising a high pressure pump variously conditionable to deliver fluid at various high pressures, a supercharger operative to deliver fluid at a relatively low pressure to said pump, means operative to condition said pump to vary the pressure of fluid delivered thereby, said means comprising a piston of small diameter and subjected at all times to the high pressure of fluid delivered by said pump and also comprising a piston of larger diameter normally subjected to the relatively low pressure of fluid delivered by said supercharger acting in opposition to the pressure of fluid acting on said small piston, and said means being responsive to an increase in the pressure of fluid acting upon said piston of larger diameter to condition said pump to operate to increase the pressure of fluid delivered thereby, and means operative to effect the flow of fluid under high pressure from said pump to said piston of larger diameter to effect the operation of the first said means.

8. A fluid pressure pump equipment comprising a high pressure pump variously conditionable to deliver fluid at various high pressures, a supercharger operative to deliver fluid at a relatively low pressure to said pump, means operative to condition said pump to vary the pressure of fluid delivered thereby, said means comprising a piston of small diameter and subjected at all times to the high pressure of fluid delivered by said pump and also comprising a piston of larger diameter normally subjected to the relatively low pressure of fluid delivered by said supercharger acting in opposition to the pressure of fluid on said small piston, and said means being responsive to an increase in the pressure of fluid acting upon said piston of larger diameter to condition said pump to operate to increase the pressure of fluid delivered thereby, control means having at least two control positions and operative to one control position to effect the flow of fluid under high pressure from said pump to act on said piston of larger diameter, and operative to its other control position to cut off the flow of fluid from said pump to said piston of larger diameter, and a choked communication always open to the fluid delivery side of said supercharger through which fluid acting upon the larger piston flows and thereby effecting a reduction in the pressure of fluid acting upon the larger piston when said control means is moved from its said one control position to its said other control position.

9. A fluid pressure pump equipment comprising a high pressure pump variously conditionable to deliver fluid at various high pressures, a supercharger operative to deliver fluid at a relatively low pressure to said pump, means operative to condition said pump to vary the pressure of fluid delivered thereby, said means comprising a piston of small diameter and subjected at all times to the high pressure of fluid delivered by said pump and also comprising a piston of larger diameter normally subjected to the relatively low pressure of fluid delivered by said supercharger acting in opposition to pressure of fluid on said small piston, and said means being responsive to an increase in the pressure of fluid acting upon said piston of larger diameter to condition said pump to operate to increase the pressure of fluid delivered thereby, control means having at least two control positions and operative to one control position to effect the flow of fluid under high pressure from said pump to act on said piston of larger diameter, and operative to its other control position to cut off the flow of fluid from said pump

to said piston of larger diameter, and means effective incident to the operation of said control means from its said one control position to its said other control position for reducing the pressure of fluid acting upon said piston of larger diameter to the pressure of fluid delivered by said supercharger.

10. A fluid pressure pump equipment comprising a high pressure pump variously conditionable to deliver fluid at various high pressures, a supercharger operative to deliver fluid at a relatively low pressure to said pump, and means operative to condition said pump to limit the pressure of fluid normally delivered by said pump, said means comprising a piston of small diameter subjected at all times to the pressure of fluid delivered by said pump and also comprising a piston of larger diameter normally subjected to the relatively low pressure of fluid delivered by said supercharger acting in opposition to pressure of fluid on said small piston, and said means being responsive to an increase in the pressure of fluid acting upon said piston of small diameter above a certain normal degree to decrease the pressure of fluid delivered thereby to said certain normal degree.

11. A fluid pressure pump equipment comprising a high pressure pump variously conditionable to deliver fluid at various high pressures, a supercharger operative to deliver fluid at a relatively low pressure to said pump, means operative to condition said pump to vary the pressure of fluid delivered thereby, said means comprising a piston of small diameter and subjected at all times to the pressure of fluid delivered by said pump and also comprising a piston of larger diameter normally subjected to the relatively low pressure of fluid delivered by said supercharger acting in opposition to pressure of fluid on said small piston, and said means being responsive to an increase in the pressure of fluid acting upon said piston of small diameter above a certain degree to decrease the pressure of fluid delivered thereby to said certain degree and also being responsive to an increase in the pressure of fluid acting on said piston of larger diameter to condition said pump to operate to increase the pressure of fluid delivered thereby, and means operative to effect the flow of fluid under high pressure from said pump to said piston of larger diameter to effect the operation of the first said means.

12. A constant speed fluid pressure pump comprising in combination a rotatable portion, a bearing portion shiftable relative to said rotatable portion for varying the volume of fluid delivered by said pump, means operative to shift said bearing portion relative to said rotatable portion, said means comprising a piston of small diameter subjected at all times to the pressure of fluid delivered by said pump and a piston of relatively larger diameter normally subjected to a relatively low degree of fluid pressure, said means being

normally responsive to the pressure of fluid acting upon said piston of small diameter to shift said bearing portion in a direction to limit the volume of fluid delivered by said pump and thereby obtain a certain degree of pressure therein, and operative in response to the pressure of fluid delivered by said pump which may act upon said piston of larger diameter to shift said bearing portion to a position in which a predetermined volume of fluid may be delivered by said pump, and means operative to effect the flow of fluid under pressure from said pump to said piston of larger diameter.

13. A fluid pressure pump equipment comprising a high pressure pump variously conditionable to deliver fluid at various high pressures, a supercharger operative to deliver fluid at a relatively low pressure to said pump, means operative to condition said pump to vary the pressure of fluid delivered thereby, said means comprising a piston of small diameter subjected at all times to the high pressure of fluid delivered by said pump and also comprising an opposing piston of larger diameter normally subjected to the relatively low pressure of fluid delivered by said supercharger, and said means being responsive to an increase in the pressure of fluid acting upon said piston of larger diameter to condition said pump to operate to increase the pressure of fluid delivered thereby, control means having at least two control positions and operative to one control position to effect the flow of fluid under high pressure from said pump to act upon said piston of larger diameter and operative to its other control position to cut off the flow of fluid from said pump to said piston of larger diameter, valve means operative to prevent the back flow of fluid under pressure from said piston of larger diameter to said pump, and a choked communication always open to the fluid delivery side of said supercharger through which fluid acting upon the larger piston flows and thereby effects a reduction in the pressure of fluid acting upon the larger piston when said control means is moved from its said one control position to its said other control position.
